Primary Examiner — Steven J Czyz(74) *Attorney, Agent, or Firm* — Bayramoglu Law Offices LLC(57) **CLAIM**

The ornamental design for a hall tree, as shown and described.

DESCRIPTION

FIG. 1 is a front perspective view of a hall tree showing my new design;

FIG. 2 is a front elevational view thereof;

FIG. 3 is a rear elevational view thereof;

FIG. 4 is a right side elevational view thereof;

FIG. 5 is a top plan view thereof;

FIG. 6 is a bottom plan view thereof;

FIG. 7 is a rear perspective view thereof; and,

FIG. 8 is a partial enlarged view of the indicated area "8" in FIG. 1.

A left side elevational view thereof is omitted since the left side elevational view thereof is a mirror image of the right side elevational view thereof.

The broken lines indicating an enlargement portion of the design form no part of the claimed design.
